AWNNG WINDOW OPERATOR

Theodore Hauck, Bellmore, N. Y., assignor to General Bronze Corporation, Garden City, N. Y.

Application December 31, 1953, Serial No. 401,628

10 Claims. (Cl. 268—104)

This invention relates to a window operator combination in which the sash may be moved to its various positions by means of a mechanism wherein the forces employed to effectuate the movements necessary to adjust the sash are exerted upon the sash through the medium of flexible but substantially longitudinally non-compressible rod or equivalent member such as a wire, and through which the forces are transmitted in directions longitudinally of said member.

One advantage of this invention lies in the fact that the necessity for such elements as cranks, levers, gearing and similar force transmitting elements between the sash and the actuator is reduced to the minimum with the result that the forces applied to open and close the window sash are converted into the maximum available power.

Another advantage of this invention lies in the fact that the device in which it is embodied is relatively simple, sturdy, easily installed and maintained and will consume a minimum of space.

In addition to these advantages a device embodying this invention will not only operate to open and close the window sash when it is actuated, but will also maintain the sash in its open and closed positions and additionally may be used to forcibly set the sash up against the weather stripping with a weather stripping compressive force.

Other advantages will appear from the description of the embodiment of the invention illustrated in the drawings and described in the specification.

While the invention is applicable to windows having sashes of different types, I shall describe it in connection with what is currently known as an awning window and it is thus illustrated in the drawings.

In these drawings:

Figure 1 is a face view of an awning type window with one light;

Figure 2 is a horizontal sectional view on line 2—2 of Figure 1 looking in the direction of the arrows;

Figure 3 is a horizontal sectional view on line 3—3 of Figure 1 looking in the direction of the arrows;

Figure 4 is a vertical sectional view on the line 4—4 of Figure 1 looking in the direction of the arrows but with the sash partly open;

Figure 5 is an enlarged view of one of the operator members and a portion of the actuator taken on line 5—5 of Figure 4;

Figure 6 is a vertical sectional view on line 6—6 of Figure 5 looking in the direction of the arrows;

Figure 7 is a horizontal sectional view on the line 7—7 of Figure 5 looking in the direction of the arrows;

Figure 8 is a horizontal sectional view on line 8—8 of Figure 5 looking in the direction of the arrows;

Figure 9 is a sectional view on line 9—9 of Figure 8 looking in the direction of the arrows; and

Figure 10 is a sectional view on line 10—10 of Figure 8 looking in the direction of the arrows.

The window to which the operator of this invention is applied and which is depicted in the drawings for illustrative purposes, comprises a frame having a header 1,

2

a sill 2 and jambs 3 as illustrated in Figure 1. Each of the jambs 3 is provided with a longitudinal, vertically extending chamber 4 as shown in Figure 3. The header 1 is provided with a longitudinal, horizontally extending chamber 5 and the sill is provided with a longitudinal, horizontally extending chamber 6 as illustrated in Figure 4 of the drawing.

The header may be provided with compressible weather stripping such as 7, the sill with a similar weather stripping such as 8 and the jambs with a weather stripping such as 9, all of which are so arranged as to be contacted by and compressed by the sash when the latter is moved into its closed position.

This sash is mounted as follows: In each of the chambers 4 in the jambs a plurality of guide rollers 9' are mounted on the jamb. An elongated slide 10 is mounted on these guide rollers for vertical movements in upward and downward directions.

Adjacent the upper end of each slide the sash 11 is pivoted at 12 to swing about these pivots into opened and closed positions.

To each side of the sash a stay-bar 13 is pivoted at 14, the stay-bar being pivoted also at 15 to the jamb.

Thus when the slides are moved downwardly the sash will be moved toward its open position about the pivots 12 and when the slides are moved upwardly the sash will be moved toward its closed position. This is because the pivots 12 move vertically with the slides while the pivots 15 have no such movement.

In order that the sash may be moved to its open position and to its closed position, maintained in such positions and sealed against the weather stripping around its entire perimeter, I have provided the following mechanism:

35 A relatively stiff, resilient and substantially non-compressible longitudinally operating member such as a wire 16 or its equivalent, is attached to each of the slides 10 at a convenient point such for instance as at its upper end as shown in Figure 4 by such means as will herein-after be described. These operating members 16 are located within the chambers 4 of the jambs and extend downwardly toward the sill in substantially rectilinear directions. They also follow rectilinear directions within the chambers 6 of the sill toward the center thereof. Between the two rectilinear portions of each operator the operator follows a curvilinear path. The two rectilinear portions are indicated by the reference numerals 17 and 18 and the curvilinear portion by the reference numeral 19.

50 The ends of these operating members 16 terminate adjacent each other preferably near the center of the sill and in overlapped relation.

When the rectilinear portions 18 are moved longitudinally outwardly, i. e. toward the respective jambs, the vertical rectilinear portions 17 will be moved upwardly, the force being applied through the curvilinear portions 19, with the result that the slides 10 will be moved upwardly. This movement will result in the closing of the sash in the manner heretofore described. When, on the other hand, the rectilinear portions 18 of the operating members are moved inwardly away from the respective jambs the slides will be drawn downwardly and the sash will be opened in the manner heretofore described.

65 In order that each operating member 16 may be maintained in such position that its movements will be longitudinally of its long axis in its rectilinear and curvilinear portions without any substantial lateral flexing and at the same time to provide a protective covering, I have provided the following:

Each of the operator members 16 is housed within a relatively rigid tubular member 20, a portion 21 of which is located within and extends longitudinally of the sill

chamber 6 and another portion 22 of which is located within and extends longitudinally of the chamber 4 in a jamb.

These two portions of the tube are substantially rectilinear and united by an integral curvilinear portion 23. These three portions of the tube determine the directions of the operating member 16.

The tube is made rigid with the window frame by suitable devices such as indicated at 23' in Figures 3, 4 and 5. It may be made integral with the window frame.

The operating member 16 is encased in a sheath and force transmitting member 24 which is preferably in the form of a helically coiled spring with insubstantial compressibility. This sheath, while snugly fitting within the tubular member 20, is capable of free sliding movement therewithin. The inside diameter of this sheath is such that the operating member 16 fits snugly therein and is thus prevented from having undesirable lateral flexing during operation.

A tubular extension 25 is mounted on and envelopes the upper end of each of the tubular members 20 and is freely movable on the tubular member. This extension 25 is secured to a bracket 26 which is provided with a bearing member 27 and is secured at 28 to the adjacent slide 10. The bearing member 27 is provided with a bore 29 through which a rod 30 freely extends. To the lower end of this rod the operating member 16 is fixedly attached. The upper end of the rod is threaded as at 31 and is provided with a locking nut 32. An adjusting nut 33 is in screw threaded engagement with this rod and is provided with a depending sleeve 34 which is fixedly secured to the extension 25 of the tubular member.

Inasmuch as the tubular member is fixedly secured to the frame of the window as at 23', the adjustment of the nut 33 will adjust the extension 25 of the tubular member on the main body portion of the latter in which position it may be locked by the lock nut 32.

Thus when the operator is originally installed the relative positions of the operator elements in respect to each other and in respect to the sash on both sides of the window may be adjusted so that in subsequent operation equal forces will be applied to both sides of the sash, thus insuring true opening and closing of the sash on the pivots without any distortionary tendency.

In order that the operators 16 may be actuated to move in both directions longitudinally of their long axes, I have provided the following mechanism: a housing 35 is provided and may be mounted on the sill in such a position as indicated in Figure 1 of the drawing. This housing is constituted preferably by a lower housing member 36 and a superimposed upper housing member 37 which are secured rigidly together, the lower member being provided with a recess 38 and the upper member with a recess 39 which together form a chamber in the housing. The lower housing member 36 is provided with aligned openings 40 and 41 which extend through the wall of the lower housing member 36. A second pair of aligned openings 42 and 43 which are substantially parallel to the first mentioned openings extend through the wall of the housing member 36 as illustrated in Figure 9 of the drawing. An end of one of the tubular members 20 is secured to the housing as at 44 in alignment with the opening 40 while an end of the other tubular member 20 which is aligned with the opening 43 is secured to the housing as at 45.

Extending from the opening 41 is an aligned extension 20' of the tubular member 20 which is aligned with the opening 41 and extending from the opening 42 is a similar extension 20'.

One of the operating members 16 is rigidly secured to a block 46 which is mounted within the tubular member 20 located within the sill of the window. The diameter of this block 46 is such that it may have free longitudinal movements within the tubular member and the length of the rectilinear portion 21 of the tubular mem-

ber is such as to permit this block to move sufficiently for the opening and closing of the window sashes.

The other of the two operating members 16 is provided with a similar block similarly mounted. The sheath 24 freely abuts the block 46 at its lower end at 24' and also freely abuts the lower end of the rod at its upper end at 24" so that when the block 46 is moved longitudinally within the tubular member 20 the operating member 16 and the sheath 24 will move as a unit with the block and with the rod 30. Rigidly connected to each block 46 is a coaxial rod 47 which is provided with a plurality of spaced abutments 48 which are rigid with the rod. The inside diameters of the portions 21 of the tubular members 20 of the extensions 20' and of the openings 40, 41, 42 and 43 are substantially the same and the diameters of the abutment members 48 are only sufficiently less than the inside diameter of the tubular members and the openings to permit free longitudinal movements of the abutment members within the same.

As will be noted from Figure 9 of the drawing, the two operating members 16 in effect overlap, but as disclosed in Figure 5 of the drawing, terminate short of the ends of the extensions 20' of the tubular members 20 so that the operating members may have freedom of movement in the tubular members longitudinally of themselves.

In order that the operating members may be moved longitudinally to open and close the sash simultaneously, I have provided the following mechanism: An actuator 30 is located within the housing 35. A disc 49 somewhat in the form of a sprocket is located within the recess 38 of the chamber of the housing 35. This disc or sprocket is provided with projections 50 and recesses 51, the projections being substantially radial and being bifurcated as shown in Figure 8 of the drawing for the reception of the rod members 47. The projections 50 are adapted to extend into the spaces between the abutments 48 and to engage the same so that upon rotation of the sprocket 49 the portions of the operating members 16 located within the chamber of the sill will be moved in opposite directions thus moving the vertical portions of the operating members either upwardly or downwardly depending upon the direction of rotation of the sprocket 49. During the engagement of the projections 50 with the abutments 48 the latter will successively seat within the recesses 51 of the sprocket as disclosed in Figure 9 of the drawing as the sprocket is rotated.

Formed rigid with this sprocket member 49 is a gear 52 which is spaced from the sprocket member by a hub 53 and is located in the recess 39 of the chamber of the housing 35, the gear being coaxial with the sprocket.

A cooperating worm 54 which is engaged with the gear 52 is suitably mounted in bearings within the housing 35 and is provided with an operating handle 55 which is accessible at the inside of the window. It may be here pointed out that the gear 45 is in the form of a helical gear which insures through the engagement of the worm 54, the maintenance of the sprocket 49 in its various positions of rest.

When the operating handle 55 is actuated the worm 54 will rotate the helical gear 52 and through the hub 53 the sprocket member 49 will be rotated in a direction dependent upon the direction of rotation of the worm 54. Because of the engagement of the sprocket member 49 with the abutments 48, the rotation of the sprocket member in one direction will cause the rods 47 to move outwardly toward the jambs. This movement of the rods will move the blocks 46 within the tubular members 20 and because of the presence of the sheath 24 and the operating member 16 and the abutment of the sheath against the block 46 and the rod 36 on each side of the window the bracket 26 will be moved upwardly, the telescopic extension 25 permitting such movement. The 75 secured of the bracket 26 on each side of the window

to the adjacent slide 10 at 28 effectuates the upward movement of the slides and consequently closes the sash.

When the operating handle 55 is actuated in the opposite direction the movement of the operating members 16 will be in the opposite direction and as a consequence the slides 10 will be drawn downwardly thus causing the opening of the sash.

It is here pointed out that when the actuator is operated to move the vertical portions of the operating members 16 upwardly the force will be transmitted to the slides 10 not only by these operating members 16 but also by the sheaths 24, the two elements on each side of the window thus forming a compound operating member during such vertical movement.

Because of the sturdiness of the construction, pressure may be applied to the operating handle 55 near the end of the closing movement of the sash so that the weather stripping will be compressed to seal the sash. The sash will be held in this closed position by the locking action of the helical gear and the worm with which the handle 55 is provided.

Each operating member 16 may be made of a relatively small diameter wire of steel but the wire may be made of various other materials having lateral flexibility and substantially no extensibility or compressibility longitudinally of itself. Moreover the sheath 24 may be made of metal or of other desirable materials which will not only guide the members 16 and assist in the movements of the slides but will also dampen any noises that may result from the movements of the operating members.

While I have illustrated and described the operator as applied to what is currently known as an awning window, it is to be understood that with certain modifications it may be adapted to operate windows of other types, such as casement windows and double hung windows, by way of example.

What I claim is:

1. An operator for moving a movable member such as a window sash comprising a stationary casing, a relatively rigid tube fixedly connected to said casing, a connector fixedly connected to said movable member, an abutment in said tube adjacent said casing, a deformable and substantially noncompressible sheath snugly fitting and movable longitudinally within said tube and abutting said abutment and said connector at its ends, a flexible operating member snugly fitting within said sheath and attached at its ends to said abutment and said connector and means for moving said abutment, said sheath, said flexible operating member and said connector in one direction to move said movable member in one direction and for moving said flexible operating member, said connector and said abutment in the opposite direction to move said movable member in the opposite direction.

2. The combination of elements recited in claim 1 wherein said tube is formed of telescopic sections, one of which is fixedly connected to said casing and the other of which is fixedly connected to said movable member.

3. The combination of elements recited in claim 1 wherein said sheath is in the form of a substantially noncompressible helical spring member.

4. The combination of elements recited in claim 1 wherein the effective length of said connector is adjustable.

5. The combination of elements recited in claim 1 in which said operating means comprises a rod which is slidable within said casing, is secured to said abutment and has spaced abutments thereon and a toothed wheel mounted within the casing and engageable with said last mentioned abutments to move said rod in both directions.

10 6. An operator for moving a movable member such as a window sash comprising a stationary casing, a relatively rigid tube fixedly connected to said casing, a first rod fixedly connected to said movable member, a second rod slidably mounted in said casing and having a series of abutments thereon, a toothed wheel mounted in said casing and engageable with certain of said abutments to move said second rod in both directions, a deformable sheath snugly mounted within and movable longitudinally within said tube and abutting at one end said first rod and at the other end the endmost of said abutments, a flexible operating member snugly mounted within and movable within said sheath and rigid at one of its ends with said movable rod and at the other of its ends with said first rod whereby when said second rod is moved in one direction, said movable member will be moved in one direction under the influence of both the sheath and the flexible operating member and when said second rod is moved in the opposite direction, said movable member will be moved in the opposite direction under the influence of the flexible operating member alone.

15 7. The combination of elements recited in claim 6 wherein said tube is formed of telescopic sections, one of which is fixedly connected to said casing and the other of which is fixedly connected to said movable member.

20 8. The combination of elements recited in claim 6 wherein said sheath is in the form of a substantially noncompressible helical spring member.

25 9. The combination of elements recited in claim 6 wherein said tube is expansible and contractible longitudinally of itself and wherein the effective length of said connector is adjustable.

30 10. The combination of elements recited in claim 6 in which said operating means comprises a rod which is slidable within said casing, is secured to said abutment and has spaced abutments thereon and a toothed wheel mounted within the casing and engageable with said last mentioned abutments to move said rod in both directions.
